MELVIN L. STONE, OF LAWRENCE, MASSACHUSETTS, ASSIGNOR TO DRAPER CORPORATION, OF HOPEDALE, MASSACHUSETTS, A CORPORATION OF MAINE.

THREAD-CUTTING TEMPLE FOR LOOMS.

Application filed April 30, 1926. Serial No. 105,692.

This invention relates to a thread cutting temple for looms such as generally employed for cutting filling ends left extending at the selvage of the cloth being woven.

5 When a loom provided with the ordinary type of thread cutting temple is stopped and the operative pieces a warp or filling end, or makes some adjustment or repair, he is very apt to move the lay back and forth and 10 as the lay, when moved forwardly to a sufficient extent, operates the temple thread cutter, it not infrequently happens that the running filling is accidentally cut. When the operative starts the loom, he usually has his 15 hand on the shipper lever and does not notice the indication of the weft fork and thus the loom starts weaving with a mispick resulting from the severed filling.

The object of the present invention is to 20 provide means for preventing the cutting mechanism from functioning when the loom is thus stopped, but which will not interfere with the normal cutting operation when the loom is running.

25 The object of the invention is further to provide a guard finger normally standing at the rear face of the temple head adjacent the movable cutter member on the thread cutting temple, together with means acting upon the 30 stopping of the loom to project this guard finger rearwardly so that it will hold the running filling away from the cutting mechanism and prevent the cutting operation even if the lay be swung back and forth while the 35 loom is still stopped.

These and other objects and features of the invention will appear more fully from the accompanying description and drawings and will be particularly pointed out in the claims.

40 As the general construction and operation of thread cutting temples and of the loom mechanism of various types is well known and familiar to those skilled in the art, it is only necessary here to illustrate and describe 45 a portion of a typical form of loom, temple and thread cutting mechanism sufficient to make clear the construction and operation of a preferred form of the present invention.

In the drawings:

Fig. 1 is a view chiefly in side elevation of 50 a portion of a loom with a thread cutting temple of an ordinary type and a preferred form of the present invention applied thereto.

Fig. 2 is a rear elevation of the temple and 55 parts immediately connected with it.

Fig. 3 is a view similar to the upper portion of Fig. 1 showing the parts in position assumed when the loom is stopped and with 60 the lay approaching its forward position.

Fig. 4 is a top plan view of the construction shown in Fig. 1.

The side frame 1 of the loom is provided with the usual breast beam 2 carrying the bracket 3, to which is bolted or otherwise secured the hollow box-like temple stand 4. The temple comprises a shank 5 and a head 6 extending transversely of the rearward end of the shank. The shank 5 is mounted to reciprocate rearwardly and forwardly in 70 the stand 4 and is normally projected rearwardly by the usual spring 7 abutting the stand at its forward end and a shoulder on the shank at its rearward end. The temple head comprises the usual cap 8, pod 9, interposed pin roll 10 and depending heel 11. At each beat-up of the lay 12, the heel 11 is struck by the lay moving the temple forwardly slightly and preventing injury to the reed 13.

The thread cutting mechanism here illustrated is of a familiar type and comprises a fixed cutting blade 14 mounted in the rear face of the head adjacent the end of the pin roll 10 and a movable cutter blade 15 mounted to slide forwardly and rearwardly in a slot in the temple head, provided at its rearward end with a hook-shaped blade portion 16 cooperating with the fixed blade 14 and provided at its forward end with a depending heel 17. The movable cutter blade 15 is normally projected rearwardly by a spring 18 of the usual type and is given its forward rocking and cutting movement by the engagement of the lay on the beat-up with the 95 depending heel 17.

Suitable means are provided for starting and stopping the loom either automatically or by hand. The only element necessary to illustrate in connection with the starting and stopping of the loom is the usual shipper lever 19 pivoted at 20 at the far side of the loom and adapted to swing from the normal running position shown in full lines in Fig. 1 to a stopping position shown in dotted lines in Fig. 1. This shipper lever element, when the loom is running, stands normally in its forward position and when the loom is stopped, it is swung to its rearward position. When the loom is started, this element is swung in the opposite direction. But any element movable between two positions for running and stopping of the loom may be employed in connection with the present invention.

A preferred form of the invention is shown embodied in a guard finger 21 preferably of comparatively thin yielding metal and preferably fork shaped, as shown in Fig. 2. This guard finger normally stands vertically at the rear face of the temple head adjacent to and straddling the hook-shaped end 16 of the movable cutter member. The guard finger is shown as depending from and integral with a shank 22 mounted to slide rearwardly and forwardly on the temple. For this purpose the shank is shown as mounted and guided in lugs 23 and 24 projecting upwardly from the temple stand 4. Cooperating stops such as a collar 25 adjustably secured by means of a set screw 26 to the shank and the lug 24 act to limit the rearward movement of the guard finger to a position, as shown in Fig. 3, where it will hold the running filling out of the field of the movable cutter blade and prevent it from engaging the filling.

A bell crank controller lever comprising a shaft 27 and arms 28 and 29 is suitably fulcrumed in brackets 30 secured to the loom frame. The arm 29 extends upwardly in the path of the shipper lever 19 and is engaged by a spring 31 acting to swing the bell crank lever rearwardly. The arm 28 extends upwardly alongside the shank 22 with its extreme end 32 directly behind a projection 33 extending laterally from a collar 34 adjustably secured by means of a set screw 35 to the shank 22. A helical tension spring 36 is connected at its rearward end 37 to the arm 28 and at its forward end to a collar 38 adjustably secured by a set screw 39 to the end of the shank 22.

The shank 22 is provided with a depending heel 40 which, when the guard finger 21 is in its rearward position, is aligned with the heel 17 of the movable cutter member, as shown in Fig. 3, and which consequently is also aligned with the depending heel 17 of the movable cutter member and 11 of the

temple when these heels are moved forward- 65 ly by the lay 12.

The parts are so arranged that when the loom is running and the shipper lever 19 is consequently in its forward running position, as shown in Fig. 1, the arm 29 70 is swung forwardly by the shipper lever against the tension of the spring 31 and through the arm 28, projection 33 and shank 22 holds the guard finger 21 snugly 75 up against the rear face of the temple head adjacent the movable cutter member. In this position the cutter member is free to function in its usual manner and will act to cut any filling ends brought within its field when the lay beats up against the heel 17. 80 When, however, the loom is stopped, and consequently the shipper lever 19 is swung to its rearward position, the bell crank lever comprising the arms 28 and 29 rocks rear- 85 wardly under the action of the spring 31, allowing the shank 22 under the action of the spring 36 to slide rearwardly until the stop 25 engages the stop 24 and the guard 90 finger 21 is brought to its rearward position shown in Fig. 3. Here the guard finger prevents the filling from being carried beneath the movable cutter member and consequently the cutting mechanism will not function to cut the filling.

With the loom stopped and the parts in 95 this position, if the operative moves the lay 12 forwardly and the lay strikes against the heel 17 of the movable cutter member, it at the same time strikes against the heel 40 and thus carries the movable cutter member and the guard finger forwardly simultaneously, the guard finger thus still preventing engagement of the filling by the movable cutter member. Consequently it is impossible for the running filling to be cut while the 100 loom is stopped as the result of any movement of the lay forwardly and rearwardly. Not until the loom is started again and the shipper lever 19 swung to its forward or starting position is the guard finger brought 110 forward to its normal position and the cutting mechanism permitted to function.

There is thus provided a very simple, effective and efficient means for preventing the 115 thread cutting mechanism from functioning when the loom is stopped. Thus there is no danger of the running filling being severed and mispicks or imperfections in the weaving of the cloth occurring.

Having thus described the invention, what 120 is claimed as new, and desired to be secured by Letters Patent, is:

1. In a loom, a temple provided with filling cutting mechanism, an element having a running and a stopping position and moved from the former to the latter position when the loom is stopped and from the latter to the former position when the loom is start- 125

ed, and means controlled by the said element acting to prevent the cutting mechanism from functioning when the loom is stopped and to permit its functioning when the loom is running.

2. In a loom, a temple provided with filling cutting mechanism including a cutter member normally projected rearwardly of the temple head, a guard finger normally standing at the rear face of the temple head adjacent the cutter member, and means acting upon the stopping of the loom to project the guard finger rearwardly to a position to prevent the cutter member from engaging the filling.

3. In a loom, a temple provided with filling cutting mechanism including a cutter member normally projected rearwardly of the temple head, a guard finger normally standing at the rear face of the temple head adjacent the cutter member, and means acting upon the stopping of the loom to project the guard finger rearwardly to a position to prevent the cutter member from engaging the filling and acting when the loom is started to return the guard finger to normal position.

4. In a loom, a temple, a cutter member movably mounted in the temple head and having a depending heel by which it is moved forwardly by the lay to cut the filling, a spring acting to project the cutter member rearwardly of the head into filling engaging position, a guard finger normally standing at the rear face of the head adjacent the cutter member and having a shank mounted to slide forwardly and rearwardly on the temple, means acting upon the stopping of the loom to project the guard finger rearwardly to prevent the cutter member from engaging the filling and acting when the loom is started to return the guard finger to normal position, a heel depending from the shank and aligned with the cutter member heel when the guard and cutter member are in forward and rearward positions whereby, if the lay be swung forwardly when the loom is stopped, the guard finger will be moved forward with the cutter member while still guarding the same against engagement with the filling.

5. In a loom, a shipper lever movable from a running position to a stopping position and vice versa to stop and start respectively the loom, a temple provided with filling cutting mechanism including a cutter member normally projected rearwardly of the temple head, a forwardly and rearwardly movable guard finger normally standing at the rear face of the temple head adjacent the cutter member, and a controller lever and means for rocking it coincidentally with the movement of the shipper lever, the said controller lever acting upon

the movement of the shipper lever to stopping position to project the guard finger rearwardly to a position to prevent the cutter member from engaging the filling and acting upon the movement of the shipper lever to running position to return the guard finger to normal position.

6. In a loom, a shipper lever movable from a running position to a stopping position, and vice versa, to stop and start respectively the loom, a temple provided with filling cutting mechanism including a cutter member normally projected rearwardly of the head, a guard finger having a shank mounted to slide forwardly and rearwardly on the temple, the said guard finger normally standing at the rear face of the temple head adjacent the cutter member, a lateral projection on the shank, a controller lever having one arm extending behind the projection on the said shank and the other arm engaging the shipper lever, a yielding connection between the said first arm and the shank tending to project the shank rearwardly, and cooperating steps on the shank and temple to limit the rearward movement of the guard finger to a position where it will prevent the cutter member from engaging the filling whereby, when the shipper lever is moved to stopping position, the guard finger will move to rearward position, and when the shipper lever is moved to starting position, the guard finger will be returned to its normal position.

7. In a loom the construction defined in claim 6, together with a heel depending from the cutter member to be struck by the lay to effect the cutting movement thereof and a heel depending from the guard finger shank and aligned with the cutter member heel when in forward and rearward positions whereby if the lay be moved forwardly with the loom stopped, the guard finger will be moved forwardly with the cutter member while still preventing engagement of the filling by the cutter member.

8. In a loom, a temple provided with filling cutting mechanism including a cutter member mounted in the temple head and movable from a position projecting rearwardly of the temple head forwardly to cut the filling, a shank mounted to slide forwardly and rearwardly on the temple and provided with a guard finger normally standing at the rear face of the head adjacent the cutter member, and means acting when the loom is stopped to project the guard finger and shank rearwardly to a position to prevent the cutter member from engaging the filling and acting when the loom is started to return the guard finger and shank to normal position.

9. In a loom, a temple provided with fill-

ing cutting mechanism including a cutter member mounted in the temple head and movable from a position projecting rearwardly of the temple head forwardly to cut the filling, a shank mounted to slide forwardly and rearwardly on the temple and provided with a guard finger normally standing at the rear face of the head adjacent the cutter member, a shipper lever for stopping and starting the loom, and means

controlled by the shipper lever acting when the loom is stopped to project the guard finger and shank rearwardly to a position to prevent the cutter member from engaging the filling and acting when the loom is started to return the guard finger and shank to normal position. 15

In testimony whereof, I have signed my name to this specification.

MELVIN L. STONE.
